UNITED STATES PATENT OFFICE.

FREDERICK J. HUMPHREY, OF KALAMAZOO, MICHIGAN, ASSIGNOR TO GENERAL GAS LIGHT COMPANY, OF KALAMAZOO, MICHIGAN.

GAS-LAMP.

953,835.

Specification of Letters Patent.

Patented Apr. 5, 1910.

Application filed April 20, 1909. Serial No. 491,009.

To all whom it may concern:

Be it known that I, FREDERICK J. HUMPHREY, a citizen of the United States, residing at the city of Kalamazoo, county of 5 Kalamazoo, State of Michigan, have invented certain new and useful Improvements in Gas-Lamps, of which the following is a specification.

This invention relates to improvements in 10 gas lamps.

The main objects of this invention are: First, to provide an improved gas lamp having inverted burners, which is of high efficiency. Second, to provide an improved 15 gas lamp which is very quickly and easily adjusted and cared for when in use. Third, to provide an improved gas lamp in which the number of burners can be readily changed and the uniform and finished appearance of 20 the lamp preserved notwithstanding such changes. Fourth, to provide in a gas lamp of the inverted burner type, improved means for supporting the burners. Fifth, to provide a gas lamp of the inverted burner type 25 which is compact in structure and graceful and attractive in appearance.

Further objects, and objects relating to structural details, will definitely appear from the detailed description to follow.

30 I accomplish the objects of my invention by the devices and means described in the following specification.

The invention is clearly defined and pointed out in the claims.

35 A structure embodying the features of my invention is clearly illustrated in the accompanying drawing, forming a part of this specification, in which:

Figure 1 is a side elevation of a structure 40 embodying the features of my invention, the outer casing being shown in vertical section. Fig. 2 is a detail view, partially in vertical section, taken on a line corresponding to line 2-2 of Fig. 3. Fig. 3 is a horizontal 45 section taken on a line corresponding to line 3-3 of Fig. 2. Fig. 4 is a horizontal section taken on a line corresponding to line 4-4 of Fig. 2, a group of four burners being illustrated by dotted lines.

50 In the drawings, similar reference characters refer to similar parts throughout the several views, and the sectional views are taken looking in the direction of the little arrows at the ends of the section lines.

55 Referring to the drawing, 1 is a gas de-

livery or gas supply pipe. At the lower end of this I preferably provide a T-shaped coupling 2, from which depend the arms 3 and 4, the arm 4 being a dummy and the arm 3 a continuation or extension of the gas supply or delivery pipe. The chimney 5 is preferably mounted upon the arms 3 and 4, a flange-like coupling member 6 being provided at the upper end of the chimney. The chimney is also preferably provided 60 with an outwardly and downwardly-projecting flange-like portion 7 at its lower end.

Through one side of the chimney is an opening 8, through which the end of the 70 burner tube 9 may be passed in assembling the lamp, the burner tube being curved or goose-neck in shape. The opening 8 is preferably provided with a closure 10 which, in the structure illustrated, is supported by the 75 pivot 11 so that it can be swung to one side to permit the introduction or removal of the burner tube 9. The closure 10 is preferably provided with a notch 12 adapted to receive the burner tube and closing onto the same so 80 that the closure assists in supporting the burner tube in position.

The burner tube 9 is preferably provided with a plurality of burners 13, which are connected to the lower end of the tube by 85 the branching arms 14, the arms being grouped around the tube 9 so that the vertical portion of the tube 9 is located centrally of the chimney and the burners are grouped centrally within the flange portion 90 of the chimney, as is illustrated.

At the lower end of the supply pipe is a valve casing 15, having an upwardly-projecting nozzle 16 thereon, a regulating valve 17 being provided for the nozzle. On the 95 nozzle is a coupling member 18 having air inlet ports therein, the ports preferably being of such size that the nozzle 17 can be manipulated through the same. The upper end of the coupling member 18 is adapted 100 to receive the end of the burner tube, see Fig. 2, and it thus assists in supporting the burner tube in position. The valve casing 15 is arranged to project through the outer casing 20, the casing being slotted at 21 to permit the adjusting of the casing when it is desired to have access to the parts within. The valve operating mechanism for the main valve 23 and the pilot valve 24 is on the 105 outside of the casing. As the details of this 110

operating mechanism forms no part of this invention, they are not described herein.

The outer casing 20 is adapted to rest upon the outwardly-projecting flange 25 mounted on the chimney. This is preferably in the form of a band adapted to embrace the flange portion of the chimney, as clearly appears from the drawing, the upper end of the band being flared outwardly. 10 The flange 25 is provided with air inlet openings 26 through which the air passes from the outer casing to the globe 27, and thence to the chimney and burners. The outer casing 20 is provided with air inlet 15 openings 28 through which the air passes to openings 26 and to the burner tube. The globe 27 is supported on the globe band 29, which is hinged at 30 to the arm 31, depending from the casing support 25. The 20 globe supporting band is held in its closed position by means of the pin 32 which engages the arm 33. The details of this are not illustrated, as they will be readily understood. The pilot burner 34 is preferably arranged 25 with its tip within the chimney, as is illustrated.

The mantles 35 are carried by the mantle support 36. This mantle support is provided with a flange 37 at its edge, adapted to 30 embrace the lower end of the chimney. On this flange are pins 38 adapted to be inserted in slots in the chimney flange, not illustrated, and engaged by the ring-like member 40 which is provided with bayonet slots 41. 35 As the details of this mantle support form no part of the present invention, they are not illustrated herein, the mantle support being preferably that described in the joint application of the applicant with Alfred H. Humphrey and Reginald Wright, filed July 13, 1908, Ser. No. 443,292.

To support the mantle support when it is released from the chimney, I preferably provide a supporting rod 42, which is arranged 45 to be vertically and pivotally adjusted in a bearing 43 secured on the outside of the chimney, so that when the mantle support is released from the chimney and dropped down, it can be swung to one side for convenience in manipulation. To assist in centering and supporting the burners, they are 50 preferably provided with outwardly-projecting lugs 44 adapted to engage with the inwardly projecting lugs or members 45 on the chimney. This prevents the lateral swinging of the burners and assists in centering and holding them in position. I illustrate the lamp as provided with three burners. These may be varied, as desired. By supporting 55 the burners in this manner, the uniform and finished appearance of the lamp is maintained throughout the variations, although the number of burners may be varied.

60 The mantle support should be changed

when the number of burners are varied, and to do this, it is only necessary to remove the nut 46 from the supporting rod 42 and supply a support adapted for the requisite number of mantles. The mantles can, however, be directly supported on the burner tips, as is the common practice in inverted lamps. 70

The outer casing 20 is preferably made up of band-like parts secured together, as 75 is illustrated, the advantage of thus forming the same being that comparatively simple dies are required. The outer casing is adjustable to afford access to the parts of the lamp within. As a convenient means 80 for holding the casing in its elevated position I provide an arm 47 which is pivoted on the arm 4 to be swung out to serve as a rest for the casing.

By forming and arranging the parts as I 85 have illustrated and described, I secure a lamp having a plurality of burners which is compact and graceful in appearance and very efficient. The structure is very easily adjusted to the particular pressure and quality of gas, a single adjusting mechanism answering for a plurality of burners. Further, an even feed for the several burners is insured. 90

I have illustrated and described my improvements in detail in the form in which I have embodied them. I am, however, aware that they are capable of considerable variation in structural details without departing from my invention but as these 100 variations will readily occur to those skilled in the art to which this invention relates, I have not attempted to illustrate or describe the same herein.

Having thus described my invention, what 105 I claim as new and desire to secure by Letters Patent, is:

1. In a gas lamp, the combination with a gas supply pipe; of a chimney mounted on said gas supply pipe and having outwardly 110 and downwardly-projecting flange like portions at its lower end, and an opening in the side thereof, said supply pipe being arranged on the outside of said chimney; an upwardly-directed gas delivery nozzle connected to said supply pipe; a curved burner tube removably arranged through said opening in said chimney and having a plurality of inverted burners on its inner end, located within said flange like portions of said chimney; a coupling member with which the outer end of said burner tube is adapted to telescope, mounted on said nozzle; and burner supporting members arranged within 115 said chimney. 120

2. In a gas lamp, the combination with a gas supply pipe; of a chimney mounted on said gas supply pipe and having outwardly 125 and downwardly-projecting flange-like portions at its lower end, and an opening in

- the side thereof, said supply pipe being arranged on the outside of said chimney; a curved burner tube removably arranged through the said opening in said chimney 5 and having a plurality of inverted burners on its inner end, located within said flange-like portions of said chimney; a closure for said opening in said chimney; and burner supporting members arranged within said chimney.
3. In a gas lamp, the combination with a gas supply pipe; of a chimney mounted on said gas supply pipe and having outwardly and downwardly-projecting flange-like portions at its lower end, and an opening in the side thereof, said supply pipe being arranged on the outside of said chimney; a curved burner tube removably arranged through said opening in said chimney and 15 having a plurality of inverted burners on its inner end, located within said flange-like portions of said chimney; and burner supporting members arranged within said chimney.
4. In a gas lamp, the combination with a gas supply pipe; of a chimney mounted on said gas supply pipe having outwardly and downwardly-projecting flange-like portions at its lower end, and an opening on the side thereof, said supply pipe being arranged on the outside of said chimney; a curved burner tube removably arranged through the said opening in said chimney and having a plurality of inverted burners on its inner end, located within said flange-like portions of said chimney; an outer casing adapted to be adjusted to offer access to said burner to permit the adjustment or removal thereof.
5. In a gas lamp, the combination with a gas supply pipe; of a chimney having an opening in the side thereof, said supply pipe being arranged on the outside of said chimney; an upwardly-directed gas delivery nozzle connected to said supply pipe; a curved burner tube arranged through the said opening in said chimney and having a plurality of inverted burners on its inner end; a coupling member with which the outer end of said burner tube is adapted to telescope, 40 mounted on said nozzle; a closure for said opening in said chimney; outwardly-projecting lugs on said burners; and lugs on said chimney arranged to coact with said lugs on said burners and with said burner tube in centering and supporting the burners.
6. In a gas lamp, the combination with a gas supply pipe; of a chimney having an opening in the side thereof, said supply pipe being arranged on the outside of said chimney; a curved burner tube arranged through the said opening in said chimney and having a plurality of inverted burners on its inner end; a closure for said opening in said chimney; outwardly-projecting lugs on said burners; and lugs on said chimney arranged to coact with said lugs on said burners and with said burner tube in centering and supporting the burners.
7. In a gas lamp, the combination with a gas supply pipe; of a chimney having an opening in the side thereof, said supply pipe being arranged on the outside of said chimney; an upwardly-directed gas delivery nozzle connected to said supply pipe; a curved burner tube arranged through the said opening in said chimney and having a plurality of inverted burners on its inner end; a coupling member with which the outer end of said burner tube is adapted to telescope, 75 mounted on said nozzle; and a closure for said opening in said chimney.
8. In a gas lamp, the combination with a gas supply pipe; of a chimney having an opening in the side thereof, said supply pipe being arranged on the outside of said chimney; a curved burner tube arranged through the said opening in said chimney and having a plurality of inverted burners on its inner end; and a closure for said opening in 80 said chimney.
9. In a gas lamp, the combination with a gas supply pipe, of a chimney having an opening in the side thereof, said supply pipe being arranged on the outside of said chimney; an upwardly-directed gas delivery nozzle connected to said supply pipe; a curved burner tube arranged through the said opening in said chimney and having a plurality of inverted burners on its inner end; a coupling member with which the outer end of said burner tube is adapted to telescope, 85 mounted on said nozzle; outwardly-projecting lugs on said burners; and lugs on said chimney arranged to coact with said lugs on said burners and with said burner tube in centering and supporting the burners.
10. In a gas lamp, the combination with a gas supply pipe; of a chimney having an opening in the side thereof; said supply pipe being arranged on the outside of said chimney; a curved burner tube arranged through the said opening in said chimney and having a plurality of inverted burners on its inner end; outwardly-projecting lugs on said burners; and lugs arranged on said chimney arranged to coact with said lugs on said burners and with said burner tube in centering and supporting the burners.
11. In a gas lamp, the combination with a gas supply pipe; of a chimney having an opening therein, said supply pipe being arranged on the outside of said chimney; a curved burner tube arranged through the said opening in said chimney and having a plurality of inverted burners on its inner end; a closure for said opening in said chimney having a slot therein to receive said burner tube when in its closed position; 110 120 125 130

outward projecting lugs on said burners; and lugs on said chimneys arranged to coact with said burners in centering and supporting the burners.

5 12. In a gas lamp, the combination with a gas supply pipe; of a chimney having an opening therein, said supply pipe being arranged on the outside of said chimney; a curved burner tube arranged through the 10 said opening in said chimney; and a closure for said opening in said chimney having a slot therein to receive said burner tube when in its closed position.

13. In a gas lamp, the combination with a 15 gas supply pipe; of a chimney having an opening therein, said supply pipe being arranged on the outside of said chimney; a curved burner tube arranged through the said opening in said chimney and having a 20 plurality of inverted burners on its inner end; outward-projecting lugs on said burners; and lugs on said chimney arranged to coact with said lugs on said burners in centering and supporting said burners.

25 14. In a gas lamp, the combination with a gas supply pipe; of a chimney having an opening therein, said supply pipe being arranged on the outside of said chimney; an upwardly-directed gas delivery nozzle connected to said supply pipe; a curved burner tube arranged through the said opening in said chimney; a coupling member with which the outer end of said burner tube is adapted to telescope, mounted on said nozzle; and a closure for said opening in said chimney adapted to engage said burner tube when in its closed position.

30 15. In a gas lamp, the combination with a gas supply pipe; of a chimney having an 40 opening therein, said supply pipe being arranged on the outside of said chimney; a curved burner tube arranged through the said opening in said chimney; and a closure for said opening in said chimney adapted 45 to engage said burner tube when in its closed position.

35 16. In a gas lamp, the combination with a gas supply pipe; of a chimney having an opening therein, said supply pipe being arranged on the outside of said chimney; an 50 upwardly-directed gas delivery nozzle connected to said opening in said chimney; a coupling member with which the outer end of said burner tube is adapted to telescope, 55 mounted on said nozzle; and a closure for said opening.

40 17. In a gas lamp, the combination with a gas supply pipe; of a chimney having an opening therein, said supply pipe being arranged on the outside of said chimney; a curved burner tube arranged through the 60 said opening in said chimney; and a closure for said opening.

45 18. In a gas lamp, the combination with a 65 gas supply pipe; of a chimney, said supply

pipe being arranged on the outside of said chimney; a curved burner tube having a plurality of burners on its inner end; outwardly-projecting lugs on said burners; and lugs on said chimney arranged to coact with 70 said lugs on said burners and with said burner tube in centering and supporting the burners.

19. In a gas lamp, the combination with a 75 gas supply pipe, of a chimney, said supply pipe being arranged on the outside of said chimney; a curved burner tube removably arranged through the wall of said opening; a burner mounted on said burner tube; and coacting lug-like members on said chimney 80 and burner, for the purpose specified.

20. In a gas lamp, the combination with a gas supply pipe, of a chimney, said supply pipe being arranged on the outside of said chimney; a curved burner tube having a 85 plurality of burners thereon removably arranged through the wall of said chimney; and burner engaging members within said chimney, coacting with said burner tube in removably supporting said burners. 90

21. In a gas lamp, the combination with a gas supply pipe, of a chimney; a burner tube having a burner thereon removably arranged in said chimney; and members within said chimney, coacting with said burner 95 tube in removably supporting said burner in an inverted position.

22. In a gas lamp, the combination with a gas supply pipe; of a chimney mounted on said gas supply pipe and having an outwardly and downwardly-projecting flange-like portion at its lower end, said supply pipe being arranged on the outside of said chimney; a valve casing connected with said gas supply pipe; an upwardly-projecting 105 gas delivery nozzle on said valve casing; a curved burner tube having a burner on its inner end located within said chimney flange; a coupling member with which the outer end of said burner tube is adapted to 110 telescope, mounted on said nozzle, said coupling member being provided with air inlet ports; and members within said chimney, coacting with said burner tube in supporting said burner. 115

23. In a gas lamp, the combination with a gas supply pipe; of a chimney mounted on said gas supply pipe and having an outwardly and downwardly-projecting flange-like portion at its lower end, said supply 120 pipe being arranged on the outside of said chimney; a valve casing connected with said gas supply pipe; an upwardly-projecting gas delivery nozzle on said valve casing; a curved burner tube having a burner on its 125 inner end located within said chimney flange; and members within said chimney, coacting with said burner tube in supporting said burner.

24. In a gas lamp, the combination with a 130

gas supply pipe; of a chimney mounted on said gas supply pipe and having an outwardly and downwardly-projecting flange-like portion at its lower end, said supply pipe being arranged on the outside of said chimney; a valve casing connected with said gas supply pipe; an upwardly-projecting gas delivery nozzle on said valve casing; a curved burner tube having a burner on its inner end located within said chimney flange; and members within said chimney, coacting with said burner tube in supporting said burner.

25. In a gas lamp, the combination with a gas supply pipe; of a chimney mounted on said gas supply pipe, said supply pipe being arranged on the outside of said chimney; a valve casing connected with said gas supply pipe; an upwardly-projecting gas delivery nozzle on said valve casing; a curved burner tube having a burner on its inner end; a coupling member with which the outer end of said burner tube is adapted to telescope, mounted on said nozzle, said coupling member being provided with air inlet ports; and members within said chimney, coacting with said burner tube in supporting said burner.

26. In a gas lamp, the combination with a gas supply pipe; of a chimney mounted on said gas supply pipe, said supply pipe being arranged on the outside of said chimney; a valve casing connected with said gas supply pipe; an upwardly-projecting gas delivery nozzle on said valve casing; a curved burner tube having a burner on its inner end; and members within said chimney, coacting with said burner tube in supporting said burner.

27. In a gas lamp, the combination with a gas supply pipe; of a chimney mounted on said gas supply pipe, said supply pipe being arranged on the outside of said chimney; a valve casing connected with said gas supply pipe; an upwardly-projecting gas delivery nozzle on said valve casing; a curved burner tube having a burner on its inner end; and members within said chimney, coacting with said burner tube in supporting said burner.

In witness whereof, I have hereunto set my hand and seal in the presence of two witnesses.

FREDERICK J. HUMPHREY. [L. s.]
